SERPENTINE PLAYGROUND CLIMBER

Robert S. Wormser, Ocala, Fla., assignor to Game Time, Inc., Litchfield, Mich.

Original design application Feb. 12, 1973, Ser. No. 331,802. Divided and this application Oct. 16, 1974, Ser. No. 515,177

Term of patent 14 years

Int. Cl. D21—03

U.S. CL. D34—5 H

FIG. 1 is a perspective view of a serpentine playground climber in accord with my new design,

FIG. 2 is a side elevational view, the opposite side being the mirror image thereof,

FIG. 3 is a front elevational view as taken from the left of FIG. 2, the rear view of the design, as taken from the right of FIG. 2, being identical,

FIG. 4 is a perspective view of a variation of a serpentine playground climber in accord with my invention,

FIG. 5 is a side elevational view of the design of FIG. 4 as taken from the right of FIG. 4, the opposite elevational side view being the mirror image thereof, and

FIG. 6 is a front elevational view of the design of FIG. 5 as taken from the left thereof.

This application being a divisional application of design application Ser. No. 331,802 entitled Playground Climber Representing an Octopus filed Feb. 12, 1973, reference

being had to the accompanying drawing, forming part thereof.

I claim:

The ornamental design for a serpentine playground climber, substantially as shown and described.
